UNITED STATES PATENT OFFICE.

FREDERICK BALLIN, OF DETROIT, MICHIGAN.

LOCK.

SPECIFICATION forming part of Letters Patent No. 297,660, dated April 29, 1884.

Application filed October 22, 1883. (No model.)

To all whom it may concern:

Be it known that I, FREDERICK BALLIN, of Detroit, in the county of Wayne and State of Michigan, have invented new and useful Improvements in Door-Locks; and I do hereby declare that the following is a full, clear, and exact description thereof, reference being had to the accompanying drawings, which form a part of this specification.

10 This invention relates to certain new and useful improvements in door-locks; and the invention consists in the peculiar construction of a hollow spindle which carries the locking-tumblers, said tumblers being actuated by 15 means of a key inserted through the spindle, and in the peculiar construction, arrangement, and various combinations of the parts, all as more fully hereinafter set forth.

Figure 1 is an elevation of a rim-lock detached from the door and with spindle broken off close above the tumblers. Fig. 2 is a section of the line *x y*, Fig. 1. Fig. 3 is a vertical section through the lock and door on the axis of the spindle. Fig. 4^a is an elevation of 25 the spindle detached from the lock, showing the spring by which the tumblers are held in their position and to prevent accidental displacement. Fig. 4^b is a section through the spindle, showing how the tumblers are held in 30 place. Fig. 5 is a longitudinal central section through tumblers adapted to be actuated from either side. Figs. 6 and 7 are views of two different keys—the key 6 for the tumblers shown in Fig. 5, and the key 7 for the tumblers shown in Fig. 3. Fig. 8 shows two cross-sections on the line *n o* and *v w*, respectively, in Fig. 4^a. Fig. 9 is a cross-section on line *r s* in Fig. 4^b. Fig. 10 is a cross-section on line *t u*, Fig. 5. Fig. 11 is an end view of the 35 tumbler, showing key in section. Fig. 12 shows arrangement of lock-case wherein my invention is applied in the construction of a mortise-lock.

In the accompanying drawings, which form 45 a part of this specification, *W* represents the lock-case, and *W'* the back plate thereof, which inclose the operating parts of the lock. *A* represents the bolt, which is kept in its extended position by the spring *S*, as in the ordinary manner. This bolt *A* is provided 50 with a leg or arm, *A'*, which operates in con-

junction with the tumblers to prevent the turning of the spindle, as hereinafter described.

T represents the spindle of my lock, and is hollow its entire length, and receives upon 55 each end a knob, *K*, to which they are removably secured in any convenient manner, and adapted to turn the spindle when the latter is not locked, as hereinafter stated.

Upon the spindle I secure the tumbler-lever *B*, by means of which the bolt *A* is retracted upon the turning of the spindle. *C* *C'* are the locking-tumblers, which project through a slot, *a*, in the spindle. The tumbler *C'* is provided with a solid pintle, *C''*, 65 which fits loosely in the spindle, and has its end so formed as to register in the end of the key. This pintle carries a pin, *C'''*, which fits loosely in the hollow pintle *C''''* of the tumbler *C'*. The ends of this pin and pintle 70 are likewise made to register conjointly with the key.

In order to keep the locking-tumblers in their adjusted positions and to prevent their accidental displacement, I place a spring, *O*, 75 in a longitudinal channel on the outer face of the spindle, and between it and the tumbler *B*. The ends of this spring are bent inwardly and project through holes in the pintle, so as to engage with recesses or notches in the 80 respective pintles of the tumblers.

In the end of each knob I secure a slotted disk, *U*, through which the key is inserted in the spindle.

In the construction above described, by inserting the key from the inside, (or lock side of the door,) the key will register with the pin *C'''* of the pintle *C''* and with the pintle *C''''*, and in consequence both pintles and their respective tumblers will in turning the key be 90 partially rotated, bringing the free ends of the tumblers in rear of the arm or leg *A'* of the bolt, being held to such position by the spring *O*, and thus prevent the turning of the spindle and a retraction of the bolt. When so locked, 95 it cannot be unlocked from the outside, as the key inserted from that end operates but one pintle and tumbler, leaving the other still in its locked position; but, on the other hand, if locked from the outside, it can be unlocked 100 from the inside.

If desired, but one tumbler may be used,

each end of its pintle being adapted to register with the key; or both tumblers may be so formed as to be operated from either side, one form of so doing being shown in Fig. 5, where-
5 in the pintle of the tumbler C' is provided with a leg or spur, which projects back and registers, in connection with the corresponding end of the pintle C'', with the key.

- To adapt this construction to a mortise-lock
10 provision must be made for inserting the spindle and tumblers, after the lock has been secured to place, in the door; and this I accomplish by cutting away a portion of the back plate of the lock and making a proper opening in the corresponding side of the door, through which the tumblers and spindle may be inserted, being retained in place by a cap, P, as shown in Fig. 12, while the opening in the door is covered by the rose.
15 20 In Fig. 1 I show a spring, Y, for retaining the locking-tumblers in their adjusted positions, which may be used instead of the spring O, if desired.

To insert the pintles, with their tumblers, into the spindle of the lock, I cut away a portion of the spindle, leaving an orifice sufficiently large through which to insert the pintles, with their tumblers projecting downward. After this has been done, I solder the piece
25 30 again to place, leaving the slot hereinbefore described, through which the tumblers project and have an easy movement, to be operated by the key; and in this construction I avoid all possible danger of the pintles and tumblers becoming lost or detached.

In Fig. 3 I show guards R as projecting into the spindle upon the outside of the door, which is designed to register with the edges of the flat key employed, and thus give greater
35 40 security against the picking of the lock by the insertion of a wrong key, even should such key register with the pintles upon its end.

The method of securing the knobs, particularly in mortise-locks, that I prefer is to form
45 the channel in which the spring O rests the entire length of the spindle, the knobs being secured to the roses, as shown in Fig. 3, so that they can turn readily without imparting any movement or strain upon the roses, while
50 upon the inside of the shanks of the knobs I form or rigidly secure a feather, which is de-

signed to fit into this recess, the knob being held to place upon the spindle merely by the screws which secure it to the door; hence in pulling upon the knob to forcibly open the door such strain is brought entirely upon the door and rose without bringing any strain whatever upon the spindle and the operating parts of the lock.
55

I am aware of the Patent No. 258,986, and make no claim to the construction shown therein.

What I claim as my invention is—

1. In a lock provided with a hollow spindle, two tumblers, the pintles of which are 65 inclosed within said spindle, and constructed and arranged substantially as specified, whereby the insertion of a key into one end of said spindle actuates both of said tumblers, while by inserting the same in the other or opposite end 70 only one of such tumblers can be operated, substantially as and for the purpose set forth.

2. In a lock, and in combination with the hollow spindle thereof, the tumblers C' C'', the latter being provided with a solid pintle upon 75 one side and a pin upon the other, said pin passing through the hollow pintle of the tumbler C, substantially as set forth.

3. In combination with the two tumblers C' C'', provided with pintles having depressions 80 or indentations, and hollow spindle T, having openings coincident with said depressions in said pintles, and provided with a longitudinal groove on its outer face, the spring O, seated in said groove, with its ends projecting through 85 said openings in the spindle and engaging with said pintles to prevent their displacement, as set forth.

4. In combination with the hollow spindle T, having a longitudinal groove and openings, 90 as described, and tumblers C' C'', provided with pintles having depressions coincident with said openings, the spring O, seated in the said groove and held therein by the tumbler sleeved on said spindle, the ends of said 95 spring being in engagement with the said pintles, substantially as and for the purpose specified.

FRED. BALLIN.
